B. DAVIDSON

WARDROBE TRUNK

Filed May 31, 1924

UNITED STATES PATENT OFFICE.

BENJAMIN DAVIDSON, OF LOS ANGELES, CALIFORNIA.

WARDROBE TRUNK.

Application filed May 31, 1924. Serial No. 717,163.

To all whom it may concern:

Be it known that I, BENJAMIN DAVIDSON, a citizen of the United States, and a resident of Los Angeles, in the county of Los Angeles and State of California, have invented new and useful Improvements in Wardrobe Trunks, of which the following is a specification.

This invention relates in general to wardrobe trunks, and more particularly to a device embodied in the trunk including means overlying the garment hangers which are slidably supported in the trunk, together with means adjustably connected therewith and adapted to be locked in position in front of the clothes or garments supported in the trunk whereby when the trunk is open unauthorized access to the garments will be prevented, and when the trunk is closed the garments and the hangers on which they are held will be firmly secured in position against movement.

It is usually customary in the manufacture of wardrobe trunks to provide a pair of horizontal rods near the sides of the trunk in one of the main compartments thereof, on which a plurality of garment hangers are removably and slidably held, and it is an object of this invention to provide a device of substantially rigid character which will overlie the upper edges of the garment hangers, together with a cross bar or other suitable means suspended substantially below the level of the first mentioned member and also adjustably held in position, and a standard connecting the upper and lower members and adapted to be locked to the lower member so that the several members when locked together will hold the garment hangers firmly in position on said rods, and against movement, and at the same time serve to hold the clothes or garments firmly within the compartment of the trunk so that they may not be displaced during the movement of the trunk.

Such a device provides means whereby when the trunk is open the garments may be locked in a compartment of the trunk without locking or closing the trunk.

Other objects may appear as the description progresses.

Although I may modify or change my invention within the scope of the appended

claims without departing from the spirit thereof, I have shown only one practical form of device in the accompanying drawings, in which:

Fig. 1 is a perspective view of a wardrobe trunk, open so as to show the general arrangement thereof, and to which my improvements are adapted to be applied.

Fig. 2 is an enlarged front elevation of the same, partly in section.

Fig. 3 is a transverse sectional elevation of the same.

Fig. 4 is a perspective view of a suitable member embodied in my invention for overlying the garment hangers for retaining them in position.

Fig. 5 is a perspective view of a cross arm embodied in my invention, adapted to be adjustably connected with the member shown in Fig. 4.

Fig. 6 is a fragmentary perspective view of a suitable latch bar two of which are employed in my invention for adjustable connection with the cross arm shown in Fig. 5.

Fig. 7 is a fragmentary view, slightly enlarged, of the device shown in Fig. 2, and constitutes a modified form of the device shown therein.

A wardrobe trunk of the character shown in Fig. 1 is adapted to be vertically disposed and to rest on one of its ends for the purpose of affording access to the interior of the trunk. The trunk is composed of two main portions as at A and B, and the portion A usually has a single compartment 1 adapted for the reception of garments which are held in position on a plurality of hangers H, H, etc. Said hangers are slidably suspended on a pair of parallel rods R, R, which are rigidly held in position in the upper portion of the compartment 1 in the portion A of the trunk.

The rods R, R have telescoping portions R' thereon by means of which the hangers may be extended outwardly from the front of compartment 1. The rods R are attached at their inner ends to a metallic bar 2 permanently secured to the rear wall 3 of the trunk and their outer ends are attached to the sides 4 of the trunk by means of brackets 5.

The upper end C of portion A, as shown in Fig. 1, is usually hinged to the rear

wall 3, so that the upper end of compartment 1 may be opened for affording access to the compartment and rendering the garments therein more readily accessible.

Now, my improvements are adapted to be applied to and connected with a trunk of the character shown in Fig. 1 by means hereinafter described, and include an upper member D, a vertical bar E, and a cross bar F, separately formed and adapted to be adjustably connected together for attaining the objects of my invention hereinbefore set forth.

The member D is clearly shown in Fig. 4, and embodies a metallic structure either of integral or composite form, but suitably ribbed so as to reinforce the same. Member D includes end portions 6, 6, which are adapted to overlie the curved portions 7, 7 of the hangers H, H, etc. The end portions 6, 6 are connected by means of side portions 8, 8, and said side portions are connected intermediate of the end portions 6, 6, by means of a ribbed portion 9. At the corners of member D, I provide vertical extensions 10, 10, etc., which have recesses 11, 11, etc., formed therein and adapted to engage and rest upon the rods R, R, which serve to support the portions 7, 7, of the hangers H. Member D is hingedly held on bar 2 by means of openings d, d, formed near the rear edge thereof, and adapted to receive bent lugs 2', 2' formed on member 2. Thus the member D may be swung backward out of contact with hinges H.

The central portion 9 of member F is provided with an elongated slot 12, and a plurality of notches 13 which are formed on opposite sides of the slot 12, the notches on one side of said slot being in registration with those on the other side, so as to receive and hold in adjusted position the upper end 14 of member E.

Member E may be provided with ribs 15 on opposite sides thereof for the purpose of lending strength thereto, and the upper portion of said member is of a width which will permit the free movement of said member between the ribs 16 at the sides of portion 9 of member D.

The upper end 14 of member E is of a width slightly greater than the width of slot 12, and is permanently secured to a cross bar F so that the ends e, e thereof will rest on the portions 6, 6 of member D at points over the rods R, R. Portion 14 of member E is also wider than the notches 13, 13 on opposite sides thereof so as to provide a shoulder which will overlie the upper surface of portion 9 when in the position shown in Fig. 2, and immediately below the portion 14 a narrower portion 17 is formed which corresponds to the width of and is adapted to seat in the notches 13, 13 on opposite sides of slot 12, so as to prevent

the member E being turned with respect to the member D.

Immediately below the portion 17 of member E a substantially narrower portion 18 is formed which corresponds substantially to the width of notch 12. Thus, the upper portion of member E when disconnected from member F would be turned at right angles by slightly elevating the member E until the portion 18 registers with the slot 12. Member E may then be moved rearwardly or forwardly in the slot 12 and then lowered so that the portion 17 will fit in two of the opposite notches 13.

The lower end 19 of member E is slidably held in a strap 20 fixed to the inner side of cross arm F and also slides through an opening 21 in the uppermost rib 22 of said member, and a lock L of any suitable form and including a member 23 attached to member E, and a member 24 attached to member F, is provided, whereby member E may be locked to the member F for preventing the movement of the device or the disconnection of the several members for affording access to the garments within the compartment 1.

On the opposite sides 4, 4 of the portion A of the trunk, I provide a pair of latch bars 25, 25, as shown in Figs. 3 and 6, which have a plurality of notches 26, 26, etc., formed on their lower edges, and which are attached at their ends 27, 27, by rivets or otherwise to the sides 4, 4 of the trunk, the central notched portions of said latch being bent outwardly for a short distance from the sides 4.

The member F is provided with a pair of ribs 22, 22 on the sides, the uppermost rib of which terminates short of the ends of the cross bar, so that the upper edge portions 28, 28 will engage and be firmly held in the notches 26 of the latch bars 25.

In operation, when the garments have been placed on the hangers H in the compartment 1, and said hangers together with rods R have been retracted into the compartment 1 of portion A of the trunk, the member D is placed in position over the upper edges of the hangers H, as shown in Figs. 1 and 2, with the portions 10 thereof resting upon the rods R. Thereafter the member E is inserted in the slot 10 and moved backwardly against the garments until the garments are tightly compressed together in the rear portion of compartment 1 so as to be incapable of movement and displacement from the hangers. Member E is then turned into the position shown in Fig. 2, and the upper end 14 thereof is seated in a pair of the notches 13. The cross bar F is then moved backwardly over the notches lower edges of latch bars 25 and against the garments for holding the lower portions of the garments firmly in position, and mem-

ber E is then locked to member F by snapping the latch portion 23 into the lock portion 24 of lock L.

The member E is preferably provided with a pin as at 29, at its lower end, or other suitable device to prevent the complete separation of the members E and F, but permitting the sufficient movement of member E relative to member F so as to effect the proper adjustment of the several parts of my device, for the purpose stated. This may or may not, however, be necessary, and is not material to my invention. Member D may be formed of sheet metal and in such case the bar E' of member E will hold member D firmly in position. If, however, member D is of sufficient strength the bar E' may be omitted.

Referring to Fig. 7, I have shown a modified form of device in which the members D and E are altered to provide probably a more preferable form of device than I have shown in Fig. 2, and especially relating to the connection between said members.

It will be noted that as shown in Fig. 4 the member D has openings between the end portions 6, 6, and the central ribbed portion 9, and the upper end of the member E' is provided with right angularly formed portions a, a on each side thereof, below the portion 17, which are integral with the end portions e, e. The portions e, e are substantially in the plane of the upper end 14 of member E, while the portions a, a, are depressed below the level of the ribs 16 of portion 9 of member D. Thus, the standard E may be elevated as shown in Fig. 7, and said standard moved transversely over the portion 9 of member D to selected positions, and when again lowered the portions e, e, thereof will rest upon the hangers H and over the rods R, R.

It will be understood from the foregoing that I have provided a satisfactory, economical and efficient device which serves to hold the clothes firmly in position in the back of the compartment 1 of the trunk, and at the same time by means of its engagement with the upper ends of the hangers H, the device serves the purpose of retaining the hangers firmly on the rods R and against displacement due to the movement and rough handling of the trunk when in shipment.

I am aware that other devices have been employed heretofore in trunks of this character for holding the clothes in position, and that devices have been embodied in the hinged portion C of the trunk when the trunk is closed for holding the hangers on the rods R, but I am not aware that anyone has heretofore embodied in a trunk of this character the several improvements hereinbefore set forth, and I desire to claim broadly thereon.

What I claim is:

1. In a wardrobe trunk having rods held in the upper end thereof, and hangers slidably disposed on said rods for supporting garments, means overlying said hangers and including members disposed in front of said garments and hangers and substantially below said hangers, adapted to be locked together for preventing unauthorized access to said garments. 75

2. In a wardrobe trunk having rods held in the upper end thereof, and hangers slidably disposed on said rods for supporting garments, means overlying said hangers and including members disposed in front of said garments and hangers and substantially below said hangers, adapted to be locked together for preventing unauthorized access to said garments, said members being adjustably connected together. 80

3. A wardrobe trunk having parallel rods fixedly held therein and garment hangers slidably and removably held thereon, a retaining member adapted to overlie the upper edges of said hangers and slidably held on said rods, a bar adjustably connected with said retaining member and adapted to be disposed in front of said hangers, and a cross bar substantially below said hangers and adapted to be locked to said other bar whereby said members will be held in selected positions for preventing unauthorized access to the garments supported on said hangers. 95

4. A wardrobe trunk having parallel rods fixedly held therein and garment hangers slidably and removably held thereon, a retaining member adapted to overlie the upper edges of said hangers and slidably held on said rods, a bar adjustably connected with said retaining member and adapted to be disposed in front of said hangers, a cross bar substantially below said hangers and adapted to be locked to said other bar whereby said members will be held in selected positions for preventing unauthorized access to the garments supported on said hangers, and means attached to the sides of the trunk for selective engagement with said cross bar for holding the cross bar in adjusted positions and against disengagement therefrom when the device is locked. 110

5. In a wardrobe trunk the combination with a pair of fixed parallel rods, and a plurality of hangers slidably and removably mounted thereon, of a retaining member overlying said hangers and supported on said rods, a cross bar substantially below said retaining member and adjustable longitudinally of said rods, and a vertical bar adjustably connected with said retaining member and slidably connected with and adapted to be locked to said cross bar, for the purpose described. 125

6. In a wardrobe trunk the combination

with a pair of fixed parallel rods, and a plurality of hangers slidably and removably mounted thereon, of a retaining member overlying said hangers and supported on said rods, a cross bar substantially below said retaining member and adjustable longitudinally of said rods, a vertical bar adjustably connected with said retaining mem-

ber and slidably connected with and adapted to be locked to said cross bar, and means attached to the sides of the trunk for engagement with said cross bar, whereby the same may be held in selected positions and against movement when the device is locked. 10

BENJAMIN DAVIDSON.
